UNITED STATES PATENT OFFICE

144,020

DESIGN FOR AN AIRPLANE

Peter Altman, Detroit, Mich.

Application August 2, 1945, Serial No. 121,168

Term of patent 14 years

(Cl. D71—1)

To all whom it may concern:

Be it known that I, Peter Altman, a citizen of the United States of America, residing at Detroit, in the county of Wayne and State of Michigan, have invented a new, original, and ornamental Design for Airplanes, of which the following is a specification, reference being had to the accompanying drawings, forming part thereof.

This application is a continuation in part of my copending application for a Design for an Airplane, Serial No. D-111,284, filed October 6, 1943.

Fig. 1 is a perspective view showing the top, front and one side of an airplane embodying my new design.

Fig. 2 is a plan view thereof.

Fig. 3 is a front elevational view thereof,

Fig. 4 is a rear elevational view thereof, and

Fig. 5 is a side elevational view thereof.

The characteristic features of my design reside in the portions shown by means of full lines in the drawings.

I claim:

The ornamental design for an airplane, as shown and described.

PETER ALTMAN.
